WHEELED SNOW SHOVEL

John W. Weingart, Waterbury, Conn.

Application April 21, 1949, Serial No. 88,715

1 Claim. (Cl. 294—54)

1

This invention relates to snow shovels, and more particularly to a shovel having small wheels or rollers for supporting the forward end of the shovel upon the surface which is to be cleared of snow.

One object of this invention is to provide a snow shovel of the above nature which will greatly reduce the expenditure of energy which is normally required in a snow-shovelling operation.

Another object is to provide a shovel of the above nature in which the wheels are so disposed laterally of the scoop as to substantially avoid interference with the normal use of the shovel.

Another object is to provide a shovel of the above nature in which the wheels are so located as to permit the user to easily control the height of the forward edge of the scoop, whereby the scoop may be selectively engaged with the surface being cleared, or supported by means of the wheels so as to facilitate forward thrusting movement of the shovel.

A further object is to provide a shovel of the above nature which will be simple in construction, inexpensive to manufacture, easy to manipulate, compact, ornamental in appearance, and very efficient and durable in use.

With these and other objects in view, there has been illustrated on the accompanying drawing one form in which the invention may conveniently be embodied in practice.

In the drawing:

Fig. 1 is a perspective view of the improved snow shovel.

Fig. 2 is a plan view of the same, a portion of the handle being broken away.

Fig. 3 is a side view, showing the shovel as it would appear in relation to a pavement or other surface being cleared of snow.

Fig. 4 is a sectional view on a larger scale, taken on the line 4—4 of Fig. 2, showing one of the wheels, and how it is mounted.

Fig. 5 is a sectional view showing the other wheel, taken on the line 5—5 of Fig. 2.

Referring now to the drawing in which like reference numerals denote corresponding parts throughout the several views, the improved snow shovel comprises an upwardly concave scoop 10, which is preferably made of sheet metal, and which has an elongated rearwardly-extending handle 11 centrally secured to the lower surface thereof by means of a sheet metal socket member 12 and rivets 13. The scoop 10 preferably has a plurality of stiffening corrugations 14.

In order to reinforce the scoop 10 and also

2

to assist in retaining snow thereon, provision is made of an upwardly-inclined rear edge portion 15, and upwardly inclined side edge portions 16, 17. The rear edge portion 15 preferably has a forwardly concave upward extension 15a secured thereto by means of rivets 15b, so that the snow will be prevented from sliding over the rear edge portion 15 during forward thrusting movement of the shovel.

10 The front edge of the scoop 10 is strengthened by means of an elongated flat steel blade 18 which is secured against the lower surface of the scoop by means of rivets 19, and which has a straight front edge 20 disposed forwardly of the edge of said scoop 10.

The opposite ends of the blade 18 are provided with integral rearwardly-extending arms 21, 22 which underlie opposite side edges of the scoop 10 and serve as bases for the securement of a 20 pair of angular wheel brackets 23, 24.

The wheel brackets 23, 24 are identical in construction, and each comprises a flat base portion 25 having a row of four equidistantly spaced apertures 26, 27, 28, 29 (Fig. 5). The base portion 25 of each bracket 23, 24 is secured against the lower surface of the arm 21 (or 22, as the case may be) by means of a pair of screws 30, 31, and nuts 32, 33 thereon. The screws 30, 31 are adapted to be engaged selectively either in the apertures 26, 28 or in the apertures 27, 29, respectively, said screws being also engaged in a single pair of apertures 32a and 33a in the scoop 10. Thus, the brackets 23 and 24 are permitted to have a forward adjustment which will be further described hereinafter.

Each of the wheel brackets 23, 24 also comprises an apertured triangular vertical ear 34 which carries a horizontal outwardly-extending headed trunnion 35 having a reduced portion 36 disposed in said arm 34 and secured by an inner swaged portion 37.

The respective trunnions 35, 35 carry a pair of small vertical wheels in the form of steel disks 38, 39 which are adapted to roll upon the pavement or other surface being cleared of snow, and thus support the forward end of the scoop 10 with the minimum of friction. The wheels 38, 39 are of a diameter which is sufficient to enable them to readily roll over small obstructions, and small enough to avoid any material interference with the normal use of the snow shovel. In practice, it has been found that wheels having a diameter of from two to three inches will operate very efficiently. Further, the wheels 38, 39 are relatively thin so that they may be pushed

forwardly through loose snow without compressing any substantial amount of snow thereunder.

It will be noted that when the screws 30, 31 are disposed in the apertures 26, 28 for securing the wheel bracket 23, as shown in Fig. 5, the forward edge of the wheel 38 is disposed a short distance behind the front edge 20 of the blade 18, this distance preferably being approximately $\frac{1}{8}$ ". Thus, while the wheel 38 may act as a fulcrum to support the blade 18 out of contact with the pavement, the operator may, if he desires, incline the shovel more steeply so as to engage the front edge 20 with the pavement, and thus permit all traces of snow to be removed therefrom.

The operator may prefer to maintain the blade 18 at a higher elevation, as for example when the shovel is to be used for clearing frozen-ground, rough driveways, or other irregular surfaces, in which case he may remove the screws 30, 31, shift the bracket 23 forwardly, and then reinsert said screws through the apertures 27, 29 so that the wheel 38 will occupy the position shown at 38' in Fig. 5. In this position the edge 20 of the blade 18 will be disposed inwardly of the periphery of the wheel 38, and thus will have additional clearance for passing over obstructions so as not to interfere with operation of the shovel.

It will be understood that the wheel bracket 24 and the wheel 39 thereon, will be adjusted in the same manner as described in connection with the bracket 23 and the wheel 38.

The wheel brackets 23, 24, and the wheels 38, 39 may be packaged in pairs by the manufacturer for sale to the user, in which case the user may apply the brackets and wheels to any suitable snow shovel. The plurality of apertures 26, 27, 28, 29 will then be found useful to permit the holding screws 30, 31 to be entered selectively through any of said apertures so as to register with the apertures which are provided in some snow shovels.

Operation

In operation, the operator will merely grasp the handle 11 and thrust the scoop 10 forwardly under a mass of snow, whereupon he may lift the shovel and throw the snow to one side in the customary manner. During the forward thrusting movement, the wheels 38, 39 will, of course, roll upon the ground or pavement so as to substantially eliminate any friction against said pavement and greatly facilitate the thrusting movement.

Further, the wheels 38, 39 will offer little resistance to forward movement through the snow, and are light in weight because of their narrow construction.

In this manner, substantially all of the snow may be removed from the pavement. If the operator should wish to scrape the pavement, he may do so merely by inclining the shovel more steeply, so as to swing the edge 20 downwardly into engagement with the pavement. When the

wheels 38, 39 are in their rearwardly adjusted positions, the operator may strike the forward edge 20 of the snow shovel against the pavement so as to shake off snow adhering thereto, without danger of damaging the wheels 38, 39.

If the operator should intend to use the shovel on irregular surfaces, he may, of course, adjust the wheels 38, 39 forwardly, as described above, so that the blade 18 may be maintained at a higher elevation, and thus will offer added clearance over projections and irregularities in the pavement or other surface being cleared.

One advantage of the snow shovel herein disclosed is that it will facilitate the cleaning of irregular or rough surfaces, inasmuch as the wheels may be adjusted so that the forward edge of the shovel will clear irregularities and small obstructions.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claim.

Having thus fully described the invention, what is claimed as new and for which it is desired to secure Letters Patent, is:

In a snow shovel, a rectangular scoop having a rearwardly-extending handle connected thereto, a pair of angular brackets connected to the base portion of said scoop immediately behind the front edge thereof, said brackets having upwardly-extending apertured ears located laterally outside of said scoop, a pair of horizontal trunnions rigidly mounted in apertures of said ears, a pair of forwardly-extending thin wheels of relatively small diameter rotatably mounted on said trunnions, the forward peripheries of said wheels lying closely adjacent the front edge of said scoop, whereby the operator may readily swing said scoop about said wheels as a fulcrum to precisely control the height of said front edge above the ground being cleared of snow.

JOHN W. WEINGART.
